UNITED STATES PATENT OFFICE.

JAMES M. HENDERSHOT, OF ATCHISON, KANSAS.

GRAIN-CLEANER.

SPECIFICATION forming part of Letters Patent No. 361,413, dated April 19, 1887.

Application filed July 21, 1886. Serial No. 208,592. (No model.)

To all whom it may concern:

Be it known that I, JAMES M. HENDERSHOT, of Atchison, in the county of Atchison and State of Kansas, have invented new and useful Improvements in Grain-Cleaners, of which the following is a full, clear, and exact description, reference being had to the accompanying drawings, forming part of this specification, in which—

10 Figure 1 represents a perspective view of a grain-cleaner embodying my improvements, and showing one side of the casing removed. Fig. 2 is a vertical longitudinal sectional view of the same. Fig. 3 is a cross sectional view 15 on the line xx of Fig. 2.

My invention relates to machines for cleaning corn and other small grain; and it consists in the peculiar construction and combination of devices, which I shall hereinafter 20 fully describe and specifically claim.

To enable others skilled in the art to which my invention appertains, I will now describe construction and indicate the manner in which the same is carried out.

25 In the said drawings, A represents a casing or frame, of any suitable construction, within which the several operative mechanisms comprising the machine are mounted.

B represents a cylinder placed horizontally 30 within the upper part of the casing and consisting of an inner screen, C, formed of small spaced iron rods extending horizontally throughout the length of the cylinder and designed to separate the cobs, silk, husks, &c., 35 from the grain, and an outer screen, D, constructed of perforated sheet metal, as shown in Fig. 1.

One end of the cylinder B is fastened to the 40 annular rim a of the spider E, which is secured to the inner end of a stub-shaft, F, while the opposite end of said cylinder is riveted or otherwise fastened to a suitable flanged head, G, having an open center, b , through which the material is fed to the cylinder. The rods constituting the screen C pass 45 through the head G and are suitably secured therein, while the screen D is riveted to the outer rim thereof, as shown in Fig. 2. The annular rim a of the spider E constitutes the 50 opposite head of the cylinder, and in conjunction with said screens and flange completes the said cylinder.

Mounted in brackets c on the frame A are small rollers H, upon the peripheries of which the open center b of the head G rests, whereby 55 said head, and consequently one end of the cylinder B, is supported.

The conveyer I is of any well-known construction and is mounted within the casing immediately below the cylinder, whereby the 60 grain from said cylinder is carried forward by said conveyer and discharged in a sheet through the opening h into a trunk, K, extending throughout the length of the casing.

The shaft L of the conveyer carries at one 65 end a pulley, d, by which power is communicated to the machine, and to the opposite end is secured a sprocket-wheel, e, which, through the medium of a belt, f, imparts motion to the sprocket-wheel g on the stub-shaft F and rotates the cylinder. The opening h , formed in the casing of the conveyer coincident with a similar opening in the trunk K, is controlled 70 by a slide, k, operated by screws l, the outer ends of which terminate in crank-handles, 75 whereby the screws are operated to adjust the slide k , and thus regulate the size of the opening h , and consequently the discharge of the grain.

By having the slide k extend nearly or quite 80 the full length of the trunk K it is evident that said slide may be adjusted to cause the grain to be discharged in a thin sheet, in order that it may be operated upon by a current of air to cause the chaff and other light foreign 85 substances to be separated from the grain, as I shall now describe.

At one side the main casing is extended to form a supplemental casing, A', having an air-trunk, P, the lower end of which is in communication with the trunk K, while in the upper portion of said casing A' a suction-fan, M, is suitably mounted on the shaft N to cause an upward current of air, which, coming in contact with the falling body of grain in trunk 95 K, readily separates from said grain all chaff and similar substance and carries the same upward into trunk P, from whence it is discharged through the outlet-pipe O, as shown in Fig. 3.

100 From the description of these several features it is obvious that small grain—such as corn—may be removed from the sheller and placed in the cylinder, where it is separated from

the pieces of cob, silk, &c., and is finally discharged through the trunk K in a thoroughly-cleaned condition. The cobs and husks that are too large to pass between the rods of the inner screen pass along the length of said screen and are discharged through or between the supporting-arms of the spider and fall into a spout or chute, B', (shown in dotted lines, Fig. 1,) said chute passing downward and having the outlet at the sill of the cleaner, from whence the material is conducted by any suitable means to the outside of the building, or at whatever point such refuse material is deposited. The two screens B and C being of the same length, it will be observed that such husks, &c., as pass through the inner screen are caught by the outer one and discharged into the chute, as before described.

Having thus described my invention, what I claim as new, and desire to secure by Letters Patent, is—

1. The frame, the cylinder B, composed of consecutive screens C and D, the casing having a discharge-opening, h, the conveyer I, the slide k, and the screws l for adjusting the slide, 25 in combination with means for rotating said conveyer and cylinder, the underlying air-trunk P, and the suction-fan M, substantially as herein described.

2. A grain-cleaner comprising a main and 30 a supplemental frame or casing, a cylinder comprising an inner and outer screen, a conveyer, an elongated trunk, K, an adjustable slide for discharging the grain in a thin sheet into said trunk, an air-trunk in communication with said trunk, a suction-fan, and a discharge-pipe, all constructed and arranged to operate substantially as herein described. 35

JAMES M. HENDERSHOT.
